UNITED STATES PATENT OFFICE.

LOUIS J. GRAFF, OF PITTSBURG, PENNSYLVANIA.

CURTAIN-POLE.

SPECIFICATION forming part of Letters Patent No. 702,723, dated June 17, 1902.

Application filed December 4, 1901. Serial No. 84,646. (No model.)

To all whom it may concern:

Be it known that I, LOUIS J. GRAFF, a citizen of the United States of America, residing at Pittsburg, in the county of Allegheny and State of Pennsylvania, have invented certain new and useful Improvements in Curtain-Poles, of which the following is a specification, reference being had therein to the accompanying drawings.

10 This invention relates to certain new and useful improvements in curtain-poles, the main object of the invention being to construct a pole by means of which a curtain may be supported without the aid of the ordinary 15 rings and pins.

Briefly described, the invention comprises a hollow pole preferably constructed of metal and which is made in two sections or members substantially equal in size. One of 20 these sections or members may be termed as a "female" section, having a spring-pocket throughout its length which receives and embraces the tongue formed on the other section. Each of the sections have their lower 25 edges turned upwardly at an incline and the upwardly-extending flanges or tongues thus formed are adapted to embrace the curtain between the same and securely hold it in position, the two sections or members of the 30 pole being locked securely after engagement by means of the sleeves placed on the ends of the pole, all of which construction will be hereinafter more fully described, and specifically pointed out in the claims.

35 In describing the invention in detail reference is had to the accompanying drawings, forming a part of this specification, and wherein like numerals of reference indicate corresponding parts throughout the several views, 40 in which—

Figure 1 is a front elevation of a curtain-pole constructed in accordance with my invention, showing a curtain supported therefrom. Fig. 2 is a detail perspective view of 45 a part of the pole, the sections or members being supported so as to clearly illustrate the construction. Fig. 3 is a like view of a part of the pole with the sections or members locked together. Fig. 4 is a like view of a 50 modified form of construction.

My improved curtain-pole is preferably and more cheaply manufactured from a suit-

able thickness of sheet metal, and a cheaper manner of manufacturing is the irregular-sided pole, as shown in Figs. 1, 2, and 3, 55 though it may be preferable to construct the pole round in cross-section, as shown in Fig. 4. In either construction, however, the pole consists of a female section 1 and a male section 2. The female section 1 has its upper 60 edge bent inwardly at an incline to form a wall 3, then outwardly to form the wall 4, these two walls forming a substantially V-shaped pocket, the edge of the section 1 being then bent downwardly at an incline, as 65 at 5, with the free edge 6 bent downwardly in a vertical manner. The section 2 of the pole has its upper edge bent downwardly to form a shoulder 6', and then bent at an incline to form the tongue 7, which is adapted to frictionally engage with the walls 3 4 of the elongated pocket in section 1. The inclined edge 5, carried by the section 1, serves as a guide to insure an easy and ready engagement of the tongue 7 with the pocket of the section 1, 70 this tongue being forced into firm engagement by pressure upon the two sections. Each of the sections has its lower edge turned upwardly at a slight incline and doubled over upon themselves to strengthen the same, this 75 upwardly-extending flange 8 of the section being adapted to embrace the curtain 9 therebetween and securely hold the same. The sections 1 and 2 of the pole are secured in a locked 80 position by means of a sleeve 10, which frictionally engages on the ends of the pole and which are preferably provided with the ornamental knobs 11 for adding to the appearance of the pole.

In operation the curtain may be placed upon 90 the flange 9 of the section 1, overlapping the same, and the section 2 is then placed in position, with the flange 8 thereof engaging the curtain and the tongue 7 forced into the pocket formed by the spring-walls 3 4 of the 95 section 1, securely binding the curtain between the two flanges at the lower edge of the sections, and the latter are then secured in a locked position by means of the sleeves 10 on the ends thereof.

In constructing the pole it will be observed that the same may be made of various forms—such as octagonal, sextagonal, or the like—and that various changes may be made in

the details of construction without departing from the general spirit of my invention.

Having fully described my invention, what I claim as new, and desire to secure by Letters 5 Patent, is—

1. A curtain-pole comprising two metal sections one having an elongated spring-pocket and the other having a tongue for engagement in said pocket, flanges formed integral 10 with said sections between which the curtain is held, and means for securing the sections in a locked position, substantially as described.

2. A hollow metallic curtain-pole comprising a male and a female section, the female section having a spring-pocket throughout its length at the upper edge, and the male section having a tongue for engagement in said pocket, and flanges carried by said sections 15

between which the curtain is held, substantially as described. 20

3. A hollow metallic curtain-pole comprising a male and a female section the female section having its upper edge bent upon itself to form a pocket and the male section having an inclined tongue for frictionally engaging 25 with the walls of said pocket, means carried by said sections at their lower edges for securing the curtain, and means engaging the ends of the sections for securing same in a locked position, substantially as described. 30

In testimony whereof I affix signature in the presence of two witnesses.

LOUIS J. GRAFF.
